UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

BRAKE-SUPPORTING MECHANISM.

1,310,032.

Specification of Letters Patent. Patented July 15, 1919.

Application filed April 5, 1918. Serial No. 226,909.

To all whom it may concern:

Be it known that I, ARMAND H. PEYCKE, a citizen of the United States, and resident of Chicago, in the county of Cook and State of Illinois, have invented certain new and useful Improvements in Brake-Supporting Mechanism, of which the following is a specification.

This invention relates to brake supporting mechanism.

One object of the invention is to improve the means for supporting brake mechanism and for maintaining said mechanism properly leveled.

Another object is to provide brake supporting mechanism adapted to meet the various requirements for successful commercial operation.

Generally speaking these and other objects are accomplished by providing in a brake mechanism, a brake, a plurality of supporting members, means connected to said supporting members, and means carried by the aforesaid means to support said brake.

The invention is illustrated on the accompanying sheets of drawings in which—

Figure 1 is a fragmentary side elevation of a railway car truck embodying my invention.

Fig. 2 is a detail view, showing the brake supporting and leveling means in front elevation.

Fig. 3 is a fragmentary side elevation of a railway car truck embodying a modification of my invention.

Fig. 4 is a detail front elevation of the modified form of supporting and leveling means, shown in Fig. 3.

Fig. 5 is a detail side elevation and Fig. 6 a detail front elevation of a modified connection between the safety bar and the resilient member which extends between the safety bars.

Fig. 7 is a fragmentary side elevation of a railway car truck embodying another modification of my invention.

Fig. 8 is a detail front elevation of the modified form of brake supporting and leveling means, shown in Fig. 7, including a three-point support arrangement.

Fig. 9 is a side elevation, and

Fig. 10 a front elevation of a modified form of supporting and leveling means, including a four-point support.

The various novel features of my invention will be apparent from the following description and drawings and will be particularly pointed out in the appended claims.

Referring first to Figs. 1 and 2 of the drawings, it will be noted that I have shown my invention in connection with a railway car truck, including a spring plank 11 to which are secured hangers 12, two of which are arranged at each of the opposite ends of the spring plank. Supported by the hangers 12 at each end of the spring plank is a safety bar 13, preferably locked to the safety hangers 12 by spring clips 14. These safety bars 13 underlie brake beams, the compression members 15 of which carry brake heads 16, having brake shoes 17, which engage the tread of the car wheels 18. Connected to each of the brake heads 16 is a hanger 19, the upper end of which is pivotally connected to any suitable part of the truck frame. Extending between the safety bars 13 near the ends thereof is a supporting member 20, preferably in the form of a spring steel strap, the central portion of which is in the form of a loop and provided with openings for the reception of a pin 21 to which is pivotally connected a hanger 22 the lower end of which is pivotally connected at 23 to a fulcrum 24, extending between the compression member 15 and tension member 25 of the brake beam. The hangers 19 support the brake rigging, including the brake beam, and hangers 22 overcome the unbalanced force of the brake beam thus maintaining the latter properly leveled in order that the braking surface of the brake shoe be maintained concentric with respect to the braking surface of the cooperating wheel. In this instance it will be noted that the hanger 22 is in the form of two relatively adjustable threaded members whereby the tension rod side of the brake beam may be raised or lowered with respect to the compression side thereof.

In the modifications shown in Figs. 3 and 4

4, the extra hanger 26 is in the form of a single piece or solid member providing for no adjustment in itself. However, it is to be noted that in the arrangements disclosed 5 in Figs. 1, 2, 3 and 4 the spring steel member 20 spanning the safety bars 13 permit a yielding vertical action in accordance with working conditions. In the event that the 10 brake beams become detached from their normal hangings they will be caught and prevented from falling to the tracks by the safety bars 13.

By referring to Figs. 5 and 6, it will be noted that the spring member 20 has its 15 ends twisted to an angle of 90° and perforated for receiving the safety bars 13 and locked on the bar by oppositely arranged spring clips 27, instead of being secured to the safety bars 13 by keys 28, as shown in 20 Figs. 1 and 2 and instead of rivets 29, as shown in Figs. 3 and 4.

By referring to Figs. 7 and 8, disclosing a modification of my invention, it will be noted that instead of having the spring 25 member extending vertically upwardly and transversely and looped at its upper end, as shown in Figs. 1 to 4, inclusive, I have provided a transversely extending spring steel member 30, which extends in a straight line 30 between and is connected to the oppositely arranged safety bars 31. The middle portion of the spring member 30 is provided with an inclined plate 32 for the reception of a sliding shoe 33, connected to the fulcrum 34 extending between the tension and compression members of the brake beam. In this modification, it will be noted that 35 only the regular hangers 35 are provided and that the tension rod side of the fulcrum 40 is supported by the plate 32 of the spring member 30, the inclined plate acting as a suitable leveling device for guiding the brake shoe to proper relationship with respect to the wheel when the brakes are applied. In this modification it will be noted 45 that a three-point support is provided, two of said points of support including hangers 35 arranged on opposite ends of the beams and the third point of support being the 50 point of contact between the spring plate 32 and coöperating sliding shoe 33.

In Figs. 9 and 10 I have shown a modification of the arrangement shown in Figs. 7 and 8 and in which there are two sliding 55 shoes 36 mounted upon the brake beam tension member 37 and which slide upon inclined portions 38 of the spring 39 which extends between and is connected to the safety bars or supports 40. In this modification 60 it will be noted that the spring has two loops, one on each side of its center and between the center point and the point of connection with the safety bars 40.

In all of these arrangements, the brake 65 mechanism is flexibly supported in a manner

whereby the brake shoes will be maintained in proper concentric association with respect to the wheels and at the same time if the 70 brake beams become detached from their normal hangings the brake beams will be caught and supported by the safety bars which will prevent said beams from falling to the tracks.

There may be other modifications of the 75 invention and it is my intention to cover all such modifications which do not depart from the spirit and scope of the following claims:

I claim:

1. In brake mechanism, safety bars, a member extending therebetween, a brake beam, brake heads carried thereby, and a hanger for supporting said brake beam, said brake beam also being supported by the member extending between said safety bars. 80

2. In brake mechanism, safety bars, a resilient member extending therebetween, a brake beam, brake heads carried thereby, and a hanger for supporting said brake beam, said brake beam also being supported by the resilient member extending between 90 said safety bars. 85

3. In brake mechanism, the combination of safety bars, a member extending between said safety bars, a brake member, and means whereby said brake member is supported by 95 said member extending between the safety bars.

4. In brake mechanism, the combination of safety bars, a member extending between said safety bars, a brake member, and means 100 whereby said brake member is movably supported by said member extending between the safety bars.

5. In brake mechanism, safety bars, a resilient member extending between said 105 safety bars, brake means, and means whereby said brake means is yieldably supported by said member.

6. In brake mechanism, the combination of safety bars, a member extending between 110 said safety bars, brake means, and a hanger connected to said member and to said brake means for supporting the latter.

7. In brake mechanism, the combination of safety bars, a spring extending between 115 said safety bars, brake means, and a hanger connected to said spring and to said brake means for yieldably supporting the latter.

8. In a brake mechanism, the combination of safety bars, a member extending therebetween, brake means, and means connected to 120 said member and brake means whereby the latter may be adjustably supported.

9. In a brake mechanism, the combination of safety bars, a yieldable member extending 125 therebetween, brake means, and means connected to said member and brake means whereby the latter may be adjustably supported.

10. In brake mechanism, safety bars, a 130

member extending therebetween, brake means, a hanger for supporting said brake means, and another hanger connected to said member and to said brake means for supporting and leveling said brake means.

5 11. In a brake mechanism, the combination of safety bars, a resilient member extending therebetween, a brake beam carrying brake heads, a hanger for supporting 10 one portion of said brake beam, and another

hanger connected to said member and to another portion of said brake beam for supporting the latter.

Signed at Chicago, Illinois, this 28th day of March, 1918.

ARMAND H. PEYCKE.
